LOUIS SCHMEISSER, OF ERFURT, GERMANY, ASSIGNOR TO RHEINISCHE METALLWAREN-UND MASCHINENFABRIK, OF DUSSELDORF-DERENDORF, GERMANY.

BREECH MECHANISM FOR SELF-LOADING FIREARMS.

No. 909,233.

Specification of Letters Patent.

Patented Jan. 12, 1909.

Application filed February 12, 1907. Serial No. 356,987.

To all whom it may concern:

Be it known that I, LOUIS SCHMEISSER, engineer, a subject of the German Emperor, residing at Erfurt, Löberstrasse 25-27th, 5 Germany, have invented certain new and useful Improvements in Breech Mechanism for Self-Loading Firearms; and I do hereby declare the following to be a full, clear, and exact description of the invention, such as 10 will enable others skilled in the art to which it appertains to make and use the same.

My invention relates to novel breech mechanism particularly designed for self-loading fire-arms, for which a stronger 15 charge of powder is used, for example, for automatic rifles and guns, as also for quick firing guns provided with recoil barrels, in which the lock is opened by the impact or backward force of the explosion.

20 This new breech mechanism, in addition to its increased strength, has the advantage of simple construction, and can be quickly and conveniently taken apart and put together again.

25 In the accompanying drawing illustrating my invention Figure 1 is a vertical section of the breech in the locked position, as seen from the left, without the top plate and trigger mechanism. Fig. 2 is a similar section of the same part showing the breech sleeve moved back at the moment in which the lock is opened, the breech piston not having recoiled further. Fig. 3 shows a section on the line A—B of Fig. 1 as seen from 30 behind.

35 In the casing A slides the breech sleeve B, at the front of which the barrel is fitted. The sleeve B is thickened at the back and adapted to carry the locking lever C which 40 turns about *c*. In the sleeve B slides the breech bolt D which carries the extractor and the firing-pin E.

The casing A is closed at the back and the recoil of the breech sleeve B and bolt D 45 is limited by the buffer F carried by the closure plate F¹, which latter is connected with the casing A by a hinge and can be so turned about the pin *f* that the parts B and D can be inserted in the casing A and taken 50 out again. In the closed position the plate F¹ is held by a bolt or screw *f*¹ which passes transversely through the plate F¹ and also through the side walls of the casing A, between which the back part of the plate F¹ 55 fits.

At the top of the casing A there is a cover G, which is connected to the casing at the front by a hinge G¹ and can be turned up. On this cover G is provided the spring casing H, which, however, can also be made 60 in one piece with said cover G. In the spring casing H is provided the sleeve J whose foot *i* engages in the part *d* of the breech bolt in such a manner that these parts describe their backward and forward 65 motion together. The part *d* of the breech bolt D, as shown in Fig. 3, is extended on one side and serves as a handle in order to enable the loading movements to be carried out or the breech to be opened for some 70 other purpose, for example to unload or in taking the fire arm to pieces.

At the back of the spring casing H the spring bolt K is provided which is connected by a bayonet joint at *k* to the cover G of the 75 spring casing H, being thus held. Further, the return spring L is provided in said casing H which spring presses at the front against the bottom of the sleeve J and at the back against the spring bolt K. The part *k* 80 of the spring bolt K has the form of a tooth and engages in a corresponding groove of the plate F (Figs. 1 and 2). As the spring L presses against the bolt K, the tooth *k* forms a spring fastening for the back part 85 of the cover G which fastening can be released by pressing against the head of the bolt K projecting at the back of the casing H.

The casing A as well as the sleeve B and 90 the cover G including the spring casing H are slotted longitudinally in order to enable the parts *d* of the breech bolt D and the part *i* of the spring sleeve J to slide back.

The forward motion of the breech sleeve 95 B is limited by its back end striking against a stop of the casing A, while the forward movement of the breech bolt D is limited by its part *d* striking a corresponding surface of the breech sleeve B, as also by its breech head striking against the back end of the barrel.

As evident from Figs. 1 and 2 the locking lever C, by its beveled rear end *c*¹ striking against the inclined surface *f*² of the buffer 105 F, is so tilted that its front end is moved out of the locking position, as soon as the breech sleeve B and barrel, as well as the breech bolt D connected to said sleeve by the locking lever C, are moved out of the position 110

shown in Fig. 1 into that shown in Fig. 2, either by the recoil or by pulling the handle of the breech bolt D.

The distance between the inclined surface 5 c^1 of the locking lever C and the corresponding surface f^2 of the plate F is so calculated that the parts B, D and C locked together must first move back through the same distance that the horizontal surface c^3 at the 10 front end of the locking lever C remains in contact with the corresponding surface a of the casing A, before said parts are unlocked. If the handle of the breech bolt D is pulled further it will recede to such an 15 extent that its back end will strike against the buffer F, while the breech sleeve B is retained by the plate F. The sleeve J connected with the breech bolt D is also moved backwards and the return spring L accordingly 20 compressed. As soon as the breech bolt D is released, the return spring L drives it forward through the agency of the sleeve J, said breech bolt first arriving in the position shown in Fig. 2. The front end of 25 the locking lever C is then forced into the locking position (Fig. 1), because the advancing power of the return spring L so influences the locking lever C through the sleeve B that its front inclined surface c^2 , 30 rides up the inclined surface a^2 of the casing A, and brings the front end of the locking lever C into the locking position when the breech bolt D is advanced to such an extent that the front end of the locking lever C can 35 move behind the same. At the moment in which the locking lever C arrives in this position the locked parts B, D and C are moved together a short distance until they arrive at the final position shown in Fig. 1 and the 40 surface c^3 of the locking lever C so bears against the surface a of the casing A that it can only be released when the locked parts B, C and D have moved back a certain distance.

45 If, now, in firing, the barrel and breech sleeve B together with the locked parts recoil, the release takes place in the manner above described. The great force with which said parts are thrown back in firing 50 causes the unlocked breech bolt D to be thrown back against the tension of the spring L by kinetic force until it is stopped by the buffer F, the gas pressure in the interior of the barrel assisting this operation, 55 which pressure, after the release has been effected, drives the empty cartridge shell backwards, together with the breech bolt D. The return spring L then drives, by means of the sleeve J, the breech bolt D forward 60 and all parts are locked in the manner above described. During this backward and forward motion of the breech bolt D all other functions necessary in self-loading fire arms are carried out in known manner; for ex-

ample, the empty cartridge shell is thrown 65 out, the trigger is raised, and a new cartridge is introduced into the barrel. In one construction of the described breech mechanism for quick firing guns the casing A is disposed to slide backwards in the same 70 manner as the barrel in guns with recoil movement. Further the necessary retarding devices and springs are provided by which the gun is kept rigidly in its firing position.

It should be mentioned that the locking 75 lever C can also be disposed at the top or side instead of at the bottom as shown in the drawing. Further two such locking levers can also be provided.

What I claim and desire to secure by Letters Patent of the United States is:—

1. In breech mechanism for automatic fire arms, the combination, with the breech casing, the breech bolt therein and a locking lever arranged to be tilted into and out of 85 the path of the recoiling breech bolt, of a buffer having an inclined face opposed to the rear end of the locking lever to tilt the same, and a removable closure to the breech casing, said closure carrying the buffer. 90

2. In breech mechanism for automatic fire arms, the combination, with the breech casing, the breech bolt therein and a locking lever arranged to be tilted into and out of the path of the recoiling breech bolt, of a 95 buffer having an inclined face opposed to the rear end of the locking lever to tilt the same, a closure hinged to the breech casing and carrying the buffer, and a pin passing laterally into the breech casing to secure 100 the buffer and closure in operative closed position.

3. In breech mechanism for automatic fire arms, the combination, with the breech casing open to the lower side, the breech bolt therein, and a locking lever arranged to be tilted into and out of the path of the recoiling breech bolt, of a buffer having an inclined face opposed to the rear end of the locking lever to tilt the same, a closure 11 hinged to the lower side of the breech casing and carrying the buffer, and a pin passing laterally into the buffer and the breech casing to secure the buffer and closure in operative closed position. 11

4. In breech mechanism for automatic fire arms, a breech casing provided with an opening, a breech bolt slidable therein, a return spring connected to the breech bolt, and a casing for said spring, the return spring casing arranged as a removable cover to the breech casing. 12

5.. In breech mechanism for automatic fire arms, a breech casing open above, a breech bolt slidable therein, a return spring connected to the breech bolt, a casing for said spring, a hinge connection between the return spring casing and the breech casing, 12

and a spring clip to secure the return spring casing in position with the opening closed.

6. In breech mechanism for automatic fire arms, a breech casing open to the upper and lower sides, a breech bolt therein, a locking lever arranged to be tilted with one end into and out of the path of the recoiling breech bolt, a buffer having an inclined face opposed to the rear end of the locking lever to tilt the same, a closure hinged to the lower side of the breech casing and carrying the buffer, a pin passing laterally into the buffer and the casing to secure the buffer in operative relation to the lever with the lower closure in place, a return spring connected to the breech bolt, a casing for said spring, a hinge connected between the return spring casing and the breech casing, a bolt serving as an abutment for the return spring and provided with a tooth engaging a recess in the breech casing to secure the return spring casing in position with the upper cover closed.

7. In breech mechanism for automatic fire arms, the combination, with the breech casing, the breech sleeve and the breech bolt therein, and a locking lever pivoted to the breech sleeve and arranged to be tilted with its forward end into and out of the path of the breech bolt, the front and rear end of the lever beveled, and the front and rear walls of the breech chamber inclined parallel to the respective beveled ends of the lever, whereby the limited longitudinal movement of the lever with the breech sleeve causes the tilting of the lever to lock and unlock the breech bolt.

8. In breech mechanism for automatic fire arms, the combination, with the breech casing, the breech sleeve and the breech bolt therein, and a locking lever pivoted to the breech sleeve and arranged to be tilted with its forward end into and out of the path of the breech bolt, the front and rear end of the lever beveled, and the front and rear

walls of the breech chamber inclined parallel to the respective beveled ends of the lever, whereby the limited longitudinal movement of the lever with the breech sleeve causes the tilting of the lever to lock and unlock the breech bolt, in combination with a return spring connected with the breech bolt, a casing for said spring carried by the upper wall of the breech chamber, said upper wall hinged to permit its opening, a clip to hold the said upper wall closed, the lower and rear walls of the breech chamber hinged to permit their swinging downward to give access to the mechanism within the chamber, and means to secure them in a closed position with the inclined rear wall in operative relation to the locking lever.

9. In breech mechanism for automatic fire arms, the combination, with the breech casing, the breech bolt therein, and a locking lever arranged to be tilted into and out of the path of the recoiling breech bolt, of a buffer removably mounted in the casing with its face opposed at an inclination to the rear end of the lever to tilt the same.

10. In breech mechanism for automatic fire arms, the combination, with the breech casing, the breech sleeve and the breech bolt therein, and a locking lever moving with the breech sleeve and arranged to be tilted with its forward end into and out of the path of the breech bolt, and the front and rear walls of the breech chamber inclined relative to the respective ends of the lever, whereby the limited longitudinal movement of the lever with the breech sleeve causes the tilting of the lever to lock and unlock the breech bolt.

In testimony whereof I have hereunto affixed my signature in the presence of two witnesses.

LOUIS SCHMEISSER.
